SLIP LAST HINGE

Henry G. Clousing, Portsmouth, Ohio, assignor to Vulcan Corporation, Portsmouth, Ohio, a corporation of Ohio

Continuation of application Serial No. 483,246, January 21, 1955. This application June 14, 1955, Serial No. 515,511

2 Claims. (Cl. 12—136)

This invention relates to a new and improved slip last hinge that is particularly adapted for use in all sizes and kinds of shoe lasts, including lasts utilized in the manufacture of shoes identified in the trade as welts, McKays, stitch downs etc. This is a continuation of my copending application Serial No. 483,246 filed in the United States Patent Office on January 21, 1955.

An object of the invention is to provide a stronger and a more positively acting collapsible shoe last, a feature of the present invention being the provision of an improved stop means for limiting collapsing movement of the heel part with respect to the last link to preclude gouging out of the heel part rout by the link when undue forces are exerted on the last to collapse it.

This and other features of the invention will become apparent from the following description taken in conjunction with the accompanying drawing wherein the same reference numerals indicate identical parts throughout the several views, and in which:

Fig. 1 is an elevational view of my slip last hinge shown in expanded condition in a shoe last that has parts thereof broken away and shown in section.

Fig. 2 is a fragmental view similar to Fig. 1 showing the last parts in collapsed positions.

Fig. 3 is a section taken on line 3—3 of Fig. 1.

Referring to the drawings, numeral 4 generally represents a collapsible shoe last having a forepart 5 and an interfitting heel part 6. The parts 5 and 6 are provided with the usual stepped or offset mating faces 8 and 9, respectively, which form cooperative shoulders on the parts for determining the expanded position of the slip last as illustrated in Fig. 1 of the drawing.

Preferably my last hinge 10 is constructed substantially in the manner described in my Patent No. 2,622,253, dated December 23, 1952, having reference also to Edward F. Schmank Patent No. 2,702,394 of February 22, 1955. The hinge 10 comprises a bowed link 11 located in aligned routs 12 and 13 formed in the last parts 5 and 6, respectively, one end of the link being pivotally connected to the forepart 5 by a transverse pin 14 anchored in said part, whilst the opposed end of the link is pivotally connected to the heel part 6 by a lateral pin 15 anchored in said part. Thus the forepart 5 and heel part 6 are connected together by the link 11 for relative swinging movements from their expanded positions shown in Fig. 1 to their collapsed position illustrated in Fig. 2, and return.

My last hinge has a stationary latch abutment which takes the form of a heightwise catch plate 16, said plate being mounted in the rout 13 by means of the pivot pin 15 passing through an aperture in its lower end and by a lateral pin 17 anchored in the heel part and passing through an opening in an intermediate portion of the plate. A latch lever 18 is pivotally mounted at its lower end on the pivot pin 14 in the forepart, said lever extending upwardly therefrom and being provided at its upper end with an abutment in the form of a rearwardly projecting portion 19 which engages the upper edge of

2

the latch abutment on the catch plate 16 to lock the last parts in extended operative positions.

As best shown in Fig. 2 the body portions of the link 11 and the latch lever 18 have substantially the same lateral dimensions across corresponding portions thereof that are disposed adjacent their common pivot pin 14, to the end that a biasing means preferably in the form of a U-shaped spring 20 encircles the pivoted ends of the link and lever and will have its ends 21 and 22 in yieldable engagement with opposed sides of the said link and lever when the hinge parts are in the inoperative, last collapsed condition illustrated in said Fig. 2. With reference to Fig. 3 it will be seen that the spring is made of flat stock having a width substantially that of the width of the rout 12 in the forepart which is just wide enough to accommodate the combined thickness of the link and lever thus preventing edgewise displacement of the spring with respect to the pivoted ends of said members. Longitudinal displacement of the spring is prevented by the curved inner wall portion 23 of the rout 12 adjacent the pivot pin 14, it also being noted that assembly of the link and the lever on pin 14 is facilitated by reason of the fact that the spring will hold the said members together in assembled position when they are inserted into the rout for insertion of the pin into their aligned pivot pin holes. When it is desired to lock the last parts in expanded condition the parts are swung on the link 11 from the position shown in Fig. 2 to their positions illustrated in Fig. 1, which brings the projection 19 on the lever into sliding contact with the upper end portion of the catch plate. This action moves the common pivoted ends of the lever and link apart thus spreading the U-shaped spring apart and putting it under tension by reason of the fact that one edge of the lever engages the spring end 22 and the opposed edge of the link 11 engages the spring end 21, said opposed edges of the link and lever moving in relatively opposite directions during closing movement of the last parts. Because this locking action is the same for all sizes of shoe lasts a uniform spring biasing tension is assured for all lasts utilizing my last hinge. Further when the hinge parts are in collapsed position the last parts are free to swing on the link 11, since the spring serves to hold the lever out of engagement with the catch plate 16.

The rear edge of the catch plate has a forwardly extending and relatively deep recess 24 formed therein in a position substantially midway between the pivot pin 15 and the pin 17 which fix the heightwise catch plate in the heel part 6. The terminal wall 25 of the recess 24 is forwardly of the pins 15 and 17 and is adapted to engage a lateral projection 26 formed on the link 11 to limit swinging movement of the heel part on the link 11 when the last parts are moved to their collapsed positions thus precluding gouging of the sole portion of the heel part body at the bottom of rout 13 by the lower edge of the link. An advantage of the construction just described is to provide a positive and extremely strong stop means for the last hinge that will withstand relatively high operational forces by reason of the fact that the projection 26 is positioned for movement within the recess 24 and engages the terminal wall 25 at the bottom of the recess which is located well forwardly of the mounting pins 15 and 17 of the catch plate 16.

Having thus described my invention and pointed out its salient features I claim as new and desire to secure by Letters Patent:

1. A shoe last comprising a forepart and a heel part having mating contact surfaces, a link connecting the forepart and heel part for relative swinging movements between collapsed and expanded conditions, said link having an abutment on the end connected to the heel part, a heightwise catch plate fixed in the heel part, said

catch plate being recessed intermediate its heightwise dimension for freely receiving said abutment, said recess having a terminal wall engageable by the abutment on the link to limit the swinging movement of the heel part on the link when the last parts are moved toward their collapsed positions.

2. A shoe last comprising a forepart and a heel part having mating contact surfaces, a link extending into slots formed in the forepart and the heel part, means for connecting the link to the forepart, a first pivot pin anchored in the heel part for connecting an end of the link to said part, said link end having a laterally projecting abutment thereon, a heightwise catch plate mounted

on the said first pivot pin, a second pivot pin anchored in the heel part and fixing the upper end of the catch plate therein, and a forwardly extending, deep recess formed in the rear edge portion of the catch plate substantially midway between the first and second pivot pins for movably receiving the abutment on the link, said recess having a terminal wall forwardly of the said pins engageable by the abutment to limit the swinging movement of the heel part on the link when the last parts are moved toward their collapsed positions.
